UNITED STATES PATENT OFFICE.

HOWARD M. DUDLEY, OF PHILADELPHIA, PENNSYLVANIA.

FIBER-TREATING DEVICE.

1,310,522.

Specification of Letters Patent. Patented July 22, 1919.

Application filed July 19, 1918. Serial No. 245,633.

To all whom it may concern:

Be it known that I, HOWARD M. DUDLEY, a citizen of the United States, residing in the city of Philadelphia, county of Philadelphia, and State of Pennsylvania, have invented certain new and useful Improvements in Fiber-Treating Devices, of which the following is a full, clear, and exact specification.

10 My invention relates to dyeing devices and refers particularly to devices suitable for the dyeing or treating with liquids of wound fiber forms, such as warp balls, cops, etc.

15 The successful dyeing of wound fibers is dependent upon the equal and uniform passage of the dye liquor through the wound fiber mass and my invention presents a device whereby this may be readily and economically accomplished.

20 In the dyeing of fiber forms of the above character, when the dyeing liquid is forced inwardly and outwardly through the forms, the force of the liquid expands or compresses 25 the forms. If these forms are compressed between fixed members and the liquid forced through them, those portions of the fiber in proximity to the compressing members will be retained from expansion, while other portions of the fiber will be allowed to expand, thus causing uneven actions of the liquid upon different portions of the mass.

20 One of the objects of my invention is a foraminous device around which the fiber is wound.

35 Another object of my invention is a device in which the dyeing liquid may be caused to pass evenly and uniformly through the device upon which the fiber is wound, and hence evenly and uniformly through the 40 fiber wound thereon.

Another object of my invention is a foraminous device upon which the fiber is wound and which will allow the compression of a 45 series of such wound fibers and the uniform passage of a liquid therethrough.

Another object of my invention is a device in which the wound fiber after compression will be held in a fixed position free 50 from disturbance during the passage of the liquid therethrough.

Another object of my invention is a device in which the wound fiber is compressed between movable members allowing of equal 55 expansion and compression of all parts of the fiber mass.

These and other objects of my invention will be evident upon a consideration of the specification and drawings.

As each individual warp ball, cop or similar form contains only a limited length of fiber, it is essential that a number of such forms be treated simultaneously in order that the operation may be economical, and as the passage of a liquid through such a fiber mass in one direction only is liable to form liquid passages through which the liquid passes more freely than through the other portions, it is advantageous to employ a device which will allow of the passage of such liquid in reverse directions through the fiber mass.

My invention discloses a device whereby these advantageous results may be obtained, and comprises broadly a foraminous spindle 75 with compressible and extensible sides, within which spindle is a hollow foraminous core capable of evenly diffusing a liquid through the foraminous spindle.

In the accompanying drawings illustrating 80 one form of my device, similar parts are designated by similar numerals.

Figure 1 is a vertical cross-section of one form of my device inclosed in a dyeing receptacle.

Fig. 2 is a top plan view of my device with the fiber wound thereon.

Fig. 3 is a section through the line 3—3 of Fig. 4 showing two foraminous spindles and cores.

Fig. 4 is a section through the line 4—4 of Fig. 3.

Fig. 5 is a fragmental development of Fig. 4 looking in the direction of the arrow 5.

Fig. 6 is a top plan view of one of the end plates.

Fig. 7 is a side plan view of one of the rods of the spindle.

Fig. 8 is a broken top plan view of the leaves of the device in closed position.

Fig. 9 is a top plan view of Fig. 7.

Fig. 10 is a top plan view of one of the rods of the spindle, showing the two portions thereof in locked position.

The particular form of the spindle of my device, illustrated in the accompanying drawings, comprises a series of spiral springs 10, 10 passing through openings 11, 11 in a series of extended members, or bars, 110 12, 12, the holes 11, 11 being sufficiently large to allow of the free movement of the

spiral spring 10 therethrough. The bars 12, 12 are composed of two members, one of which carries the extended members 12^A, 12^A capable of placement through the openings 12^B, 12^B of the other member the members having the openings 12^C and 12^D for the passage of the locking pin 12^E.

The end of each spiral spring 10 is curved inwardly to allow it to pass a bar 12. Each 10 bar 12 carries a series of extended members 50, 50 to prevent the bars from sliding toward each other into positions less than the length of the members 50, 50, the object of the members 50, 50 being to prevent the bars 15 12, 12 from sliding together and thus causing a collapse of the spindle.

The core of the device as illustrated, comprises a hollow foraminous member 13 formed by a series of inwardly and outwardly extended angular members having vertical openings 14, 14 upon one side thereof and horizontal openings 15, 15 upon the other side thereof.

The method of arranging the spindles and 25 cores, and of passing a liquid through them in reverse directions, is shown in Fig. 1. This device comprises a dyeing chamber 16 formed by the hollow cylindrical member 17, having the flanges 18 and 19. The flange 30 19 is attached to the flange 20 of the bottom 21 by means of the screw bolts 22, 22. The bottom 21 is connected by means of the pipe 23 to a source of liquid supply and is also connected to the drain pipe 24, carrying 35 the valve 25. The flange 18 is movably connected to the flange 26 of the top 27, by means of the wing-screw bolts 28, 28, which pass through an opening in the flange 26 and thread within an opening in the flange 40 18. A pipe 29 connects the top 27 with a source of liquid supply. The top 27 has an annular partition 30 which is extended inwardly into the stepped member 31, 32, 33. The annular hollow step 31 forms a tubular 45 opening 34. The step 32 has two inwardly extended members 35 and 36 spaced from each other and forming a recess 37. The top 27 also contains an extended annular member 80 capable of close engagement with 50 the inner face of the tubular member 17 and slidably thereon.

Integral with the lower portion of the interior of the cylinder 17 is an annular member 38 supported on the member 17 by the 55 supporting members 39, 39. The member 38 has the two inwardly extended members 40 and 41 spaced from each other and forming the recess 42.

Over the upper face of the member 38 is 60 a plate 51, having openings 52, 52. Movable over the upper face of the plate 51 is a series of members 53, 53, each carrying the segmental members, or leaves, 54, 54, 55, 55, the ends of which are beveled and pass over 65 the corresponding leaves of the adjacent

member 53. The extension 56 of the member 53 slides over the upper face of the plate 51, and the extension 57 of the member 53 allows of the placement of a fiber form 100 thereupon. Each member 53 carries an arm 70 58, having openings 59, 59, through which rods 60, 60 are connected by the springs 61, 61, thus binding together the series of members 53, 53. It will thus be seen that the leaves 54, 54 press against the rods 12, 12, 75 and that the members 53, 53 are capable of moving inwardly and outwardly with the corresponding movement of the rods 12, 12 and the fiber 100.

A similar plate 51' and members 53' 53', 80 with their attached parts are capable of placement under the step 33 in the upper portion of the device.

As the members 53, 53 are forced outwardly, the leaves 54, 54 will slide over each 85 other, as will the leaves 55, 55. As the extremities of the leaves 54, 54 are forced outwardly, they will abut upon the extremities of the leaves 55, 55, thus forming a tight joint as shown in Fig. 8.

90 A series of rods 62, 62, having the turn buckles 63, 63, pass through the openings in the plates 51, 51' and can be employed for moving said plates and compressing the fiber between them.

95 It is evident from the above that the entire fiber mass will move equally inwardly and outwardly with the pressure of liquid passed through it, as the members 53, 53, 53', 53', between which the fiber is compressed, 100 will slide over the plates 51, 51'.

The operation of the device is as follows:—

A core is placed within the dyeing receptacle, the outer face of the lower portion of 105 which abuts tightly upon the inner face of the member 51, forming a tight joint therewith. A series of spindles is wound with the fiber 100, 100 and are placed in adjacent position to each other, the extended members 110 12, 12 of adjacent spindles being staggered with respect to each other, the members 53, 53, 53', 53' are placed upon the two ends, the plates 51, 51' are placed upon the members 53, 53, 53', 53' and drawn together 115 by means of the rods 62, 62 and the turn buckles 63, 63 until the desired compression is obtained. This device is then placed within the dyeing chamber and around the core 13, the lower extended members 12, 12 of 120 the lower spindle being situated within the recess 42.

The top 27 is then placed in position, the upper extended members of the upper spindle being inserted within the recess 37. 125 The top is then moved inwardly by means of the screw bolts 28, 28 until the member 33 rests upon the plate 51'. A dye liquor is then forced through the pipe 23 and thus passes through the bottom 21, the dyeing

chamber 16, the wound fiber 100, the foraminous spindle into the interior of the foraminous core from which it passes through the tubular member 34 into the top 27 and through the pipe 29 for continuous circulation.

If the flow of liquid be reversed, it will pass through the pipe 29 into the top 27 and thence through the tubular member 34 into the interior of the core 13 and thence outwardly through the foraminous core, the foraminous spindle and the wound fiber into the receptacle 16 from which it passes through the bottom 21 and the pipe 23 for continuous circulation.

It is to be noted that the construction of the foraminous core 13 is of such a character as to allow the liquid passing therethrough to be impinged equally and evenly over the inner surface of the wound fibers and that the construction of the spindle is such as to allow this equal and uniform impinging of the liquid to be unimpeded, thus allowing the circulation of the liquid to be even and uniform through all portions of the various wound fibers.

I do not limit myself to the particular size, shape, number or arrangement of parts as described and shown, all of which may be varied without going beyond the scope of my invention as described and claimed.

What I claim is:—

1. In a fiber treating device, in combination, a spindle comprising a series of spiral springs each carrying a series of spaced members capable of having fiber wound thereon.

2. In a fiber treating device, in combination, a spindle comprising a series of spiral springs each carrying a series of spaced members capable of having fiber wound thereon and imperforate end members capable of abutment upon the fiber having a longitudinal movement over the spindle.

3. In a fiber treating device, in combination, a spindle comprising a series of spiral springs each carrying a series of spaced members capable of having fiber wound thereon and imperforate end members capable of abutment upon the fiber having a longitudinal movement over the spindle and expandable movement with the spaced members.

4. In a fiber treating device, in combination, a series of spaced members capable of having fiber wound thereon, spring means connecting the spaced members allowing of their expandable movement and imperforate end members capable of abutment upon the fiber having a longitudinal movement over the spindle and expandable movement with the spindles.

5. In a fiber treating device, in combination, a series of spaced members capable of having fiber wound thereon, spring means connecting the spaced members allowing of

their expandable movement, imperforate end members capable of abutment upon the fiber having a longitudinal movement over the spindles and expandable movement with the spindles and abuttable segmental members carried by the end members forming a liquid impervious annular element at varying expanded positions of the spaced members.

6. In a fiber treating device, in combination, a series of spaced members capable of having fiber wound thereon, means connecting the spaced members allowing of their expandable movement, imperforate end members capable of abutment upon the fiber having a longitudinal movement over the spindles and expandable movement with the spindles, and imperforate members exterior of, and abuttable upon, the end members over which the end members are capable of slidable movement.

7. In a fiber treating device, in combination, a spindle comprising a series of spiral springs each carrying a series of spaced members capable of having fiber wound thereon, imperforate end members capable of abutment upon the fiber having a longitudinal movement over the spindle and means for compressing the fiber.

8. In a fiber treating device, in combination, a spindle comprising a series of spiral springs each carrying a series of spaced members capable of having fiber wound thereon, imperforate members capable of abutment upon the fiber having a longitudinal movement over the spindle and expandable movement with the spaced members and means for compressing the fiber.

9. In a fiber treating device, in combination, a series of spaced members capable of having fiber wound thereon, means connecting the spaced members allowing of their expandable movement, imperforate end members capable of abutment upon the fiber having a longitudinal movement over the spindles and expandable movement with the spindles and means for compressing the fiber.

10. In a fiber treating device, in combination, a series of spaced members capable of having fiber wound thereon, means connecting the spaced members allowing of their expandable movement, imperforate end members capable of abutment upon the fiber having a longitudinal movement over the spindles, abuttable segmental members carried by the end members forming a liquid impervious annular element at varying expanded positions of the spaced members and means for moving the end members compressing the fiber.

11. In a fiber treating device, in combination, a series of spaced members capable of having fiber wound thereon, means connecting the spaced members allowing of their expandable movement, imperforate end mem-

bers capable of abutment upon the fiber having a longitudinal movement over the spindle and expansible movement with the spindles, imperforate members exterior of, and abuttable upon, the end members over which the end members are capable of slide-
5 able movement, and means for moving the

exterior members with respect to each other compressing the fiber.

Signed at New York in the county of New 10
York and State of New York this 15 day
of July, 1918.

HOWARD M. DUDLEY.
